UNITED STATES PATENT OFFICE.

HUGO UNGER, OF BERLIN, GERMANY, ASSIGNOR TO THE FIRM OF LINTZ & ECKHARDT,
OF BERLIN, GERMANY.

HEMSTITCH SEWING-MACHINE.

1,252,745.

Specification of Letters Patent.

Patented Jan. 8, 1918.

Application filed January 5, 1916. Serial No. 70,435.

To all whom it may concern:

Be it known that I, HUGO UNGER, a subject of the King of Saxony and German Emperor, residing at 8 Wilhelm Stolzestrasse, 5 Berlin, Germany, have invented certain new and useful Improvements in Hemstitch Sewing-Machines; and I do hereby declare the following to be a full, clear, and exact description of the invention.

10 My invention relates to hemstitch sewing machines and more particularly to the piercer and means for changing the stroke of the same, so that the piercer may remain in the fabric when the direction of feed is changed. 15 Heretofore when the direction of feed was changed after a straight seam was made, the new seam was not in the proper relation to the other seam and the corner of the two seams was not sewn exactly. This results 20 from the fact, that the fabric in turning often is shifted with relation to the needles, so that the needles and the piercer lifted to the upper position before the fabric was turned, cannot enter in their downward 25 movement exactly in the holes, made previously in the fabric.

According to the invention an exact joining of the new seam is obtained by the fact, that in turning the fabric the stroke of the 30 piercer is altered in such a manner, that the piercer remains in the fabric. The fabric therefore may be turned but it cannot be shifted.

Means are provided for effecting the 35 change of the stroke of the piercer without the help of the hands, which are necessary to guide the fabric.

Another object of the invention is to provide means for locking the presser foot in its 40 upper position when the stroke of the piercer has been changed.

A form of construction of the invention is shown as an example in the accompanying drawings.

45 Figure 1 is a front view of the machine; Fig. 2 a side view, partly in section on line A—B of Fig. 1; Fig. 3 a plan view; Figs. 4 to 6 are details of the essential parts of the machine in different positions; Fig. 7 shows 50 a modification.

The two needles *a a'* which can be moved up and down and spread in a known manner, are fastened on the needle bars *b b'*, hinged to the head *b²*. This head is provided with a circumferential groove, in

which engages the fork *c'* of the bar *c*, acted upon in a known manner by a cam, not shown in the drawing. The presser *d* is fastened on the lower end of the presser bar *d'*, the upper end of which is pivotally connected with the sleeve *d²*. A pin *d³* of this sleeve engages the vertical bar *f* which can be moved up and down in the guides *f³ f⁴*. A lateral projection *f²* of this bar is acted upon by the lower arm *t'* of a lever *t*, pivoted on the stud *t²*. The upper end of this lever is provided with a roller *t³* resting against the cam *f'*. This cam is fixed on a counter shaft *f⁶* which is journaled in the arm *f⁷* and connected with the main shaft *o* 60 by suitable gearing (not shown) adapted to drive the counter shaft at a slower speed than that of the main shaft, the purpose of which will be hereinafter explained. The shape of the cam *f⁶* is such that when its 65 raised portion engages the roller *t³* of the arm *t*, the latter is suddenly lowered and the arm *t'*, bar *f*, sleeve *d²* and presser bar *d'* are lifted. To quickly return these parts to their initial positions, a spring *f⁵*, which 70 tends to depress the bar *f*, is connected at one end to the bar *f* and at the other end to the guide *f⁴*.

The lower part of the presser bar *d'* is provided with a lateral arm or loop *d⁶* which 75 is actuated by the lower arm of the lever *d⁵*, pivotally arranged on the stud *d⁴*. Against the upper beveled arm of this lever rests a lateral projection *g⁸* of a vertical bar *g*, movable in the guides *g'* and *g²*. The upper 80 end of this bar is provided with a lateral projection *g³*, resting against the under side of a lever *g⁴*, pivotally arranged on the stud *g⁵*. The free end of this lever rests on the cam *g⁹* fixed on the main shaft *o*. A spring 85 *g⁶*, fixed at one end to the frame of the machine and bearing with the other end against a projection *g⁷* of the bar *g*, tends to lift this bar. When the cam *g⁹* rotates the bar *g* is moved up and down and by means of the 90 lever *d⁵* the presser bar *d'* with the presser *d* is shifted to and fro, while it is moved up and down at the same time by the action of the cam *f'* on the lever *t* and the spring *f⁵* on the bar *f*, the arrangement being such, 95 that the fabric *h* is fed after each third stitch of the needles.

Between the needles *a a'* the piercer *i* is arranged, which is detachably fastened to the bar *i'*. This bar is connected to the arm 100

55 110

k' of the bar *k* slidable in the guides *k⁴* and *k⁵*. On the rear side of this bar is provided an arm *k²* to which is pivotally connected a lever *l*. In the upper end of this lever an *L* shaped slot *m* is provided, engaged by the pin *n'* of a bell-crank lever *n*, pivotally arranged on the stud *n³*. The upper end of this lever carries a pin *n²* engaging a cam-cylinder *o'* fixed on the main shaft *o*. By 10 the rotation of this cam cylinder the lever *n* is rocked and the bar *k* and the piercer *i* are moved up and down.

Normally the pin *n'* lies in the right end of the cross arm of the *L* shaped slot *m*, as 15 shown in Figs. 2 and 5, and in this position of the pin *n'* the stroke of the piercer *i* is such, that the piercer in its upper position is out of the fabric *h*, as shown in Figs. 1 and 2, so that the fabric may be shifted by 20 the presser *d*. If the direction of the seam is to be changed, the stroke of the piercer is diminished to such a degree, that the piercer also in its upper position remains in the fabric, as shown in dotted lines Fig. 6. 25 For this purpose on the underside of the bed-plate *p* a bell crank lever *q* is arranged, rotatable on the stud *q'*. This lever is connected by the rod *r* to another bell crank lever *r'*, pivotable on the stud *r⁴*. The lever *r'* is connected by the rod *r²* with the lever *l*. If the lever *q* is moved in the direction of the arrow, shown in Fig. 2, by the knee of the person using the machine, the lever *l*, in the lower position of the bar *k* and 30 piercer *i*, is moved toward the right hand into a hole *e³* of the plate *e'*, as shown in Fig. 6. The pin *n'* in the movement of the lever *n* is moved in the vertical part of the *L* shaped slot while the lever *l* and the parts 35 connected with it are maintained in their position, until the pin *n'* reaches the end of the slot. In the further upward movement of the pin *n'* the lever *l*, the bar *k* and the piercer *i* are lifted against the action of the 40 spring *k³*. But this upward movement of the bar *k* and the piercer is so small, that the point of the piercers is not lifted out of the fabric, but remains in the same, as 45 shown in dotted lines Fig. 6. In this position the fabric may be turned while the presser is in its upper position, but it cannot be shifted with relation to the needles. The pin *n'* in its following downward movement moves firstly idle in the vertical slot, 50 until it reaches the lower end of the same, whereupon the lever *l* and the piercer *i* are moved downward, until they reach the position, shown in full lines in Fig. 6.

The presser *d* must be lifted, if the fabric 55 is to be turned. This is preferably effected automatically by changing the stroke of the piercer. For this purpose the following means are provided. To the bent lever *r'* a second rod *r³* is fastened which runs nearly 60 parallel to the rod *r²* and is supported by

the projection *s* of the frame. The free end of this rod rests in the lower position of the presser against the arm *t'* of the lever *t*. If the presser is in its upper position, while the needles and the piercer are 70 in the lower position, the free end of the rod *r³* can be moved by turning the lever *q*, under the lifted arm *t'* of the lever *t*, as shown in dotted lines Fig. 4, so that the lever *t*, the bar *f* and the presser *d* are 75 locked in the upper position. In the mean time the rod *r²* is moved along for changing the stroke of the piercer, as above described. In this locked upper position of the presser, the fabric can be turned around the piercer 80 remaining in the fabric, and the corner of the seam can be sewn exactly, as the fabric cannot be shifted in this position of the presser. By releasing the lever *q* the rods *r r' r²* are returned by the spring *u* into 85 normal position, so that the rod *r³* releases the lever *t* and the presser *d* and the lever *l* is brought into the position shown in full lines in Fig. 2. The piercer *i* therefore will 90 have its full stroke.

In the modification shown in Fig. 7 the lever *l'* carries a pin *l²* engaging an inclined slot *v* of the lever *n*. If the lever *l'* is drawn to the left hand by the rod *r²* until the pin *l²* rests against the end of the slot, 95 the stroke of the piercer-bar *k* will be diminished, the pin *l²* working on a shorter lever arm. The piercer therefore will remain in the fabric also in its upper position.

I claim as my invention:

1. In a sewing machine, the combination of needle bars, means for reciprocating the same, needles carried by the bars, a piercer arranged between the needles, means for reciprocating the piercer, feeding mechanism for the fabric including a presser, and means for changing the stroke of the piercer and holding it in the fabric during the upper position of the presser.

2. In a sewing machine, the combination of needle bars, means for reciprocating the same, needles carried by the bars, a piercer arranged between the needles, means for reciprocating the piercer, feeding mechanism for the fabric including a presser, 105 means for changing the stroke of the piercer and holding the point of the latter below the fabric, and means for locking the presser in raised position.

3. In a sewing machine, the combination of needle bars, means for reciprocating the same, needles carried by the bars, a piercer arranged between the needles, means for reciprocating the piercer, feeding mechanism for the fabric, a lever pivotally connected at one end with the piercer, a bell crank lever slidingly connected to the other end of the aforesaid lever, and a cam on the machine shaft for actuating the bell-crank lever.

4. In a sewing machine, the combination of needle bars, means for reciprocating the same, needles carried by the bars, a piercer arranged between the needles, means for reciprocating the piercer, feeding mechanism for the fabric, a lever pivotally connected at one end to the piercer and provided on its other end with an L-shaped slot, a bell-crank lever having a pin engaging said slot, a driving shaft, and means on the latter for rocking the bell-crank lever.

5. In a sewing machine, the combination of needle bars, means for reciprocating the same, needles carried by the bars, a piercer arranged between the needles, means for reciprocating the piercer, feeding mechanism for the fabric, a lever pivotally connected at one end to the piercer and provided in its other end with an L-shaped slot, a bell-crank lever having a pin engaging said slot, a driving shaft, means on the latter for rocking the bell-crank lever, and means for changing the position of the slotted lever relatively to said pin.

25 6. In a sewing machine, the combination of needle bars, means for reciprocating the

same, needles carried by the bars, a piercer arranged between the needles, means for reciprocating the piercer, means for changing the stroke of the piercer, feeding mechanism for the fabric including a vertically reciprocating bar, and means automatically operated by the stroke changing means for locking the said bar in raised position.

7. In a sewing machine, the combination of needle bars, means for reciprocating the same, needles carried by the bars, a piercer arranged between the needles, means for reciprocating the piercer, feeding mechanism for the fabric including a vertically reciprocating bar, a movable rod for locking the said bar in raised position, a bell crank lever arranged on the under side of the machine, and means connecting the movable rod with the bell crank lever.

In testimony whereof I have signed my name to this specification, in the presence of two subscribing witnesses.

HUGO UNGER.
